(57) **CLAIM**

The ornamental design for a surgical instrument, as shown and described.

DESCRIPTION

FIG. 1 is a perspective, bottom, right side view of a surgical instrument showing our new design according to a first embodiment.

FIG. 2 is a top view of our new design shown in FIG. 1.

FIG. 3 is a bottom view of our new design shown in FIG. 1.

FIG. 4 is a front view of our new design shown in FIG. 1.

FIG. 5 is a rear view of our new design shown in FIG. 1.

FIG. 6 is a right-side view of our new design shown in FIG. 1.

FIG. 7 is a left-side view of our new design shown in FIG. 1.

FIG. 8 is a perspective, bottom, right side view of a surgical instrument showing our new design according to a second embodiment.

FIG. 9 is a top view of our new design shown in FIG. 8.

FIG. 10 is a bottom view of our new design shown in FIG. 8.

FIG. 11 is a front view of our new design shown in FIG. 8.

FIG. 12 is a rear view of our new design shown in FIG. 8.

FIG. 13 is a right-side view of our new design shown in FIG. 8; and,

FIG. 14 is a left-side view of our new design shown in FIG. 8.

The broken lines consisting of short broken lines show the remaining portions of the surgical instrument that form no part of the claimed design.

The APPENDIX, comprising pages 1-15 and incorporated herein by reference as part of the disclosure of this application, shows further illustrations of embodiments of the above-referenced design. The broken lines consisting of dot-dash lines in the embodiments included in the Appendix are boundary lines that show that the claimed designs extend

(Continued)

to the boundary line but do not include the boundary line. The yellow highlighted lines may be disclaimed in these embodiments.

In any of the embodiments shown in FIGS. 1-14 or the Appendix, the surgical instrument may be, but is not limited to, a surgical guide.

1 Claim, 14 Drawing Sheets
